UNITED STATES PATENT OFFICE

ARTHUR DICKERSON, OF LOGAN, UTAH

CARBURETOR

Application filed June 16, 1931. Serial No. 544,825.

My invention relates to carburetors and has for its object to provide a new and efficient and highly economical carburetor for use on internal combustion engines.

5 A further object is to provide a carburetor for internal combustion engines which will be simple in construction, economical to manufacture, simple in operation and one in which the choke lever acts both as a choke and 10 as a means of regulating the mixture of fuel introduced into the said engine. The medium of regulating the mixture being a big factor in the necessary changes needed for different altitudes, for various weather conditions and for winter and summer driving.

15 A still further object is to provide a carburetor which cannot get out of adjustment, one in which the slow speed adjustment is easily and quickly made and one in which the 20 high speed adjustment may be made richer or thinner as desired by the operator with a semi-automatic regulation of the mixture taking place all the time the engine is running.

25 A still further object is to provide a carburetor which has the high speed adjustment automatic in so far as the mixing of the air with the fuel preparatory to introducing it into the engine. This adjustment is commensurate with the speed, the revolutions per minute of the engine, and the suction allowed through the carburetor by the amount of opening through the throttle valve.

30 A still further object is to provide a carburetor which will be easy to install and which will be so constructed as to be adaptable to any car, as the inlet for the fuel may be rotated if desired to any position.

35 These objects I accomplish with the device illustrated in the accompanying drawings in which similar numerals and letters of reference indicate like parts throughout the several views and as described in the specification forming a part of this application and pointed out in the appended claims.

40 In the drawings in which I have shown the best and most preferred manner of building my invention

45 Figure 1 is a side elevation of the carburetor.

50 Figure 2 is a plan view thereof.

Figure 3 is a side elevation of the upper portion of the carburetor removed.

Figure 4 is a side elevation of the sliding air control valve.

Figure 5 is a vertical diametrical section on 55 line 5—5 of Figure 2.

Figure 6 is a vertical diametrical section of the air control valve.

Figure 7 is an inverted plan view of the valve shown in Figure 6 with the control 60 or choke lever shown in connection therewith.

65 In the drawings I have shown the carburetor as made of three sections A, B, and C. The section A is the top portion of the device and extends down through the other two sections to which and by which they are secured. The section B is the float chamber cover, and the section C is the float chamber.

70 The section A is made with a flanged top 1 by which it may be secured to the intake manifold of an internal combustion engine by passing tap bolts through the holes 2.

75 Onto the bottom of the top 1, I then provide a cylindrical mixing throat or draft chamber 3, and the bottom end of the mixing chamber is constricted to a centrally bored extension 4 in the central bore 5 of which the metering fuel jet 6 is screwed. The valve 6 is secured in rigid position in the bore by a set screw 7. The extension 4 is surrounded 80 by the float chamber C, and the fuel for the device enters the valve bore 5 through the port 8, below the level of the bottom of the jet 6.

85 The top side of the float chamber cover B is provided with a curved depression 9 to fit against the curved portion 10 of the extension 4 and the cover is centrally bored to receive the extension and to allow the extension to be passed down therethrough said depression 9 to be fitted snugly to the portion 10.

90 The float chamber C is then placed around the bottom of the device and secured therearound by a stud bolt 11 being screwed through a hole 12 in the bottom of the chamber C and up into the bottom end of the bore 5 of the extension 4. A washer 13 prevents leakage of fuel from around the bolt 11. The bolt 11 holds the cover to the section A, 95 and the float chamber C, to the cover B, 100

and holds the entire assembly together by the one bolt, enabling quick removal of parts for replacement or cleaning or installation.

Onto the top side of the cover B, I then provide a gas inlet boss 14 to which the lead line from the fuel supply is attached and a float 15 is mounted onto the bottom side of the cover, with a control valve 16 carried thereover, actuated by a curved member 17 secured on the top side of the float adjacent the pivot point 18. The control valve 16 controls the flow of fuel through the boss 14 into the float chamber and keeps the level of the fuel in the chamber near a constant level.

Primary air ports 20 are bored through the bottom of the draft chamber 3 through the tapered bottom 2a thereof into open connection with the bore 5 above the top of the jet 6.

The top end of the jet 6 is tapered inwardly and the holes or ports 20 enter the bore 5 in alignment with the tapered end so that a portion of each is just above the top of the jet and the balance of the hole directs air around the top end of the jet. This position of the jet may be varied up or down, commensurate with the amount of fuel desired, but when once adjusted for any certain motor the jet will not be changed.

Around the mixing chamber 3 near the top end thereof, I then provide an annular chamber 21 which chamber 21 is formed by a top 22 extending from the side wall of the chamber 3 and a cylindrical side wall 23 depending from the top 22 forming the annular chamber therewithin. A flange 24 is formed on the outside edge of the bottom side of the wall 23 to provide means for attaching an air cleaner to the entire device and as a base to mount the control lever for choking the motor.

Within the annular chamber 21 and surrounding the chamber 3, I then provide a suction controlled floating valve 25, which valve is formed of a flat annular top 26 and a depending cylindrical sleeve 27. Segments are cut from the side walls of the chamber 3 leaving openings 28 through which air is introduced into the mixing chamber and the cylindrical valve has segments cut from the walls of the sides thereof leaving semi-circular openings 29 adapted to be brought into alignment with the openings 28 or to close off the openings 28 as required for operation. The lower edge of the side of the openings close off the ports 20 sufficiently to allow the engine just enough air to mix with the fuel for idling the engine when choking for starting. The secondary air is then allowed to enter the mixing chamber through the openings 28 and 29 to provide for running and acceleration.

A fuel control valve or metering pin 30 is suspended from a support bar 31 down into

the end of the jet 6 to control the amount of fuel allowed to pass through the end of the jet.

The support bar 31 is screwed in through the side wall of the sleeve 27 of the valve 25 and the end of the bar is slotted at 32 and made smaller at 33 so that the hole in the end 34 of the valve 30 may be passed over the end of the bar and the slotted end will contact to allow it to pass thereover and will then expand to hold the valve thereon. This attaches the valve 30 in suspension from the valve 25 so that when the valve 25 is raised the valve 30 will be raised from the jet 6 and as the valve 25 allows more air to enter the ports 28 and 29 into the mixing chamber the valve 30 simultaneously allows more fuel to be sucked up through the jet 6, thereby making the amount of air and fuel commensurate with each other. On the top of the chamber 21 I provide a radial boss 35, which boss has a central bore 36 to communicate with the interior of the chamber 3. A transverse hole or port 37 is bored from the chamber 21 into the bore 36 to provide direct suction from the chamber 3 into the chamber 21. An adjustable needle valve 38 is screwed into the bore 36 and has the end tapered to shut or partially shut off the suction through the bore 36 and the port 37. The suction from the chamber 3 in the top of the chamber 21 draws the top plate of the valve 25 up, drawing the cylinder sleeve 27 up, opening the ports 28 and 29, allowing air to enter therethrough and at the same time opening the jet 6 by raising the valve 30 therefrom, thus drawing more fuel through the jet as the air is drawn in through the ports 28 and 29. The suction from the motor is controlled by a butterfly valve 40 mounted in the bore of chamber 3.

A choke control lever 41 is mounted on the under side of the flange 24, and the said lever is of the bell crank type having the choke wire 43 secured to the usual set screw means, 45 in the end of the lever and having the other leg of the lever bifurcated to engage a vertical stand pipe or cylindrical bar 44 which bar when actuated by the lever partially rotates the valve 25 around the chamber 3 closing or nearly closing the primary ports 20 and closing the ports 28 and 29, thus shutting off sufficient air from the engine to choke for starting. The instant the engine starts the suction therefrom draws the valve 25 up, opening more of the primary air and if the suction is sufficient, opening the ports 28 over the ports 29, allowing some secondary air to enter with the fuel. This is regulated by atmospheric conditions and the speed of the engine or the amount the throttle valve is opened. A needle valve 46 is carried in the bore of the bar 44, said valve having the top end tapered with the bottom end to move freely in the bore of the bar 44. The needle valve is long enough to touch the top of the

chamber 21 and extends down to the cover B, so that there is no movement of the valve up or down. Ports 47 are bored through the walls of the bar 44 near the top or near the junction thereof with the valve 25 and these ports are opened and closed by the raising and lowering of the valve 25, raising and lowering the bar 44 up or down on the needle valve. The higher the valve 25 is raised the more the ports are opened, thus the less suction is created above the valve in the chamber 21. This is to break the suction in the chamber 21 and regulate the level to which the valve will be raised upon opening the 15 throttle valve. This feature eliminates fluttering of the valve 25, making the mixture even and smooth, yet at the same time making the device operate more responsively to each opening of the throttle valve.

20 The operation of my carburetor is as follows:

To choke the carburetor for starting the operator pulls out the choke wire 43, thereby pulling the lever 41, rotating the valve 25, 25 partially shutting off the primary air ports 20, and the openings 29, allowing only a little air to enter through the ports 20. The motor starts and as soon as it is rotating the suction will draw through the chamber 3 and will 30 draw the valve 25 up by the suction through the ports 36 and 37. This action opens the openings 28 by bringing the openings 29 into alignment therewith allowing secondary air to enter the chamber 3 and at the same time 35 drawing the metering pin 30 up out of the jet 6, drawing more fuel up through the jet 6 to be mixed with both the primary and secondary air.

As the motor warms the choke lever may 40 be returned to the point at which the motor operates most efficiently. This places the openings 28 and 29 in more direct alignment with each other and as the motor is accelerated the valve 25 is raised commensurately 45 with the amount of air and fuel required.

Each acceleration of the motor or retardation varies the level of the valve 25 proportionately with the amount of fuel and air being used and in direct relation to the speed 50 of the motor. The needle valve 46 will regulate the level of the valve 25 and prevent over action and over travel of the valve 25.

Having thus described my invention I desire to secure by Letters Patent and claim:

55 1. In a carburetor of the class described for internal combustion engines the combination of a mixing chamber having an extension thereunder adapted to receive a metering fuel jet; a float chamber and cover carried under 60 said chamber; a jet carried in said extension; an annular chamber formed around said mixing chamber; a suction controlled secondary air control valve carried around said mixing chamber, said valve having a portion forming 65 the lower wall of said annular chamber;

means for communicating the suction from said engine to said annular chamber; openings through said mixing chamber to form secondary air openings and to be opened or closed by said air control valve; radial primary air ports leading through the base of said mixing chamber into the interior thereof at approximately the level of the metering jet; a metering valve carried in said metering jet and supported and actuated by said secondary air control valve; means to partially rotate said air control valve to shut off all of the secondary air openings to said chamber and all or part of said primary air to start the motor; and a needle valve carried between 70 said annular chamber and said float chamber 75 cover adapted to control the opening or closing of ports into said annular chamber as necessary for control of the movement of the secondary air control valve.

2. In a carburetor the combination of a three section assembly secured together by the medial extension of the top piece passing down through the other two pieces and having a stud bolt secured thereto; a mixing 90 chamber formed in the top section; a float chamber in the bottom section and a cover for said float chamber formed by the medial section; a suction operated valve in an annular chamber formed around the mixing chamber, said valve being adapted to open and close air ports formed in the wall of the mixing chamber; means to break the suction from the engine in said chamber; means to control the flow of fuel into said chamber by the 95 movement of the air control valve; and means to rotate the valve in the annular chamber to choke the engine.

In testimony whereof I have affixed my signature.

ARTHUR DICKERSON.
